HYDRAULIC PUMP OR MOTOR

Elek K. Benedek, Bucyrus, Ohio

Application October 16, 1935, Serial No. 45,326

16 Claims. (Cl. 103—161)

This invention relates to hydraulic pumps or motors and more particularly to hydraulic pumps or motors of the kind including a plurality of radially disposed, circumferentially spaced piston and cylinder assemblies. Pumps or motors of this general character are well known in the art.

The main object of this invention is to provide a pump or motor of the class referred to embodying novel and improved structural features by virtue of which efficiency of operation is increased and manufacturing and assembling costs decreased as compared to pumps of the prior art.

15 Another object is to provide in such a pump or motor, an improved organization of parts for effecting relative reciprocation between the pistons and associated cylinders.

Another object is to provide an improved arrangement for transmitting torque directly from a piston reactance member to a cylinder barrel, or from the cylinder barrel to the reactance member independently of the pistons.

Another object is to provide a pump or motor 25 of the class referred to having a compact construction and arrangement of parts whereby machines of a given capacity will occupy less room than machines of the same class previously known.

30 Another object is to provide improvements in the pump or motor disclosed in my copending application Serial Number 681,991, filed July 24, 1933. Further objects will become apparent from a reading of the following description, the appended claims and the accompanying drawings, in which:

Figure 1 is a longitudinal sectional view of a pump or motor embodying the invention, the section being taken on the line 1—1 of Figure 2 and parts of the casing being broken away.

40 Figure 2 is a transverse sectional view taken on the line 2—2 of Figure 1.

Figure 3 is a detail sectional view taken on the line 3—3 of Figure 1.

45 Figure 4 is a perspective view of a slide block. Figure 5 is a view similar to Figure 2, but showing a modification.

Figure 6 is a detailed view of part of the structure shown in Figure 5 and drawn on an enlarged scale, the section being taken on the line 5—6 of Figure 7.

Figure 7 is a section taken on the line 7—7 of Figure 6.

55 Figure 8 is a detail view in side elevation showing a roller element; and

Figure 9 is an end elevation of the roller element shown in Figure 8.

For the purposes of disclosure the embodiments of the invention shown in the drawings will be described as operating as pumps but it 5 will be understood that like other machines of the same general class, they also are adapted for operation as hydraulic motors.

The pump shown in Figures 1 to 4, inclusive, 10 comprises a casing formed by end plates 1 and 2 provided with flanges, (not shown), or an intervening connecting central casing part. The end plate 1 is formed with a bore 3 which receives a pintle 4 having a snug press fit in the bore 3. The pintle is formed with a tapered part 5 flanked by cylindrical bearing surfaces 6 and 7. A cylinder barrel 9 formed with a tapered bore 10 and with cylindrical bearing races or surfaces 11 and 12, is mounted for rotation about the pintle. In the form shown roller bearings 13 and 14 are interposed between the pintle bearing surfaces 6 and 7 and the respectively associated cylinder barrel bearing surfaces 11 and 12. The cylinder barrel is formed with an oil chamber 16 located at the right hand end of the pintle for containing lubricant for the bearings 14. The cylinder barrel is adapted to be rotated by means of a shaft extension 17 which may be connected to any suitable source of power (not shown).

15 The cylinder barrel fits snugly over the pintle in order to prevent leakage of fluid being pumped under high pressure and it is therefore necessary that the pintle act to some extent as a bearing for the rotatable cylinder barrel. The pintle itself does not provide the main bearing support 20 for the cylinder barrel as will become apparent hereinafter, but it is desirable that the roller bearings 13—14 be employed in order to reduce friction to a minimum. The main bearing support for the cylinder barrel is provided by the 25 casing itself. In the form shown the cylinder barrel is formed at each end with seats 18 in which are mounted bearing races 19 for ball bearings 20 cooperating also with races 21 mounted in seats 22 formed in the casing end plates 1 30 and 2. The bearing assemblies 19, 20 and 21 provide the main support for the cylinder barrel and as stated above the bearings 13 and 14 are employed merely to minimize the friction between the pintle and the cylinder barrel, even 35 though the pintle is not relied upon for carrying any substantial load as a bearing.

The cylinder barrel is formed with a plurality of radially disposed, circumferentially spaced cylinders 23 which are adapted to communicate 40

with the barrel bore 10 by means of passages 24. In the plane of the passages 24 the pintle is formed with ports 25 adapted to communicate successively with the cylinder passages 24 when 5 the cylinder barrel is rotated, the pintle ports 25 being in constant communication with pintle passages 26, leading to the inlet and discharge pump connections. Pistons 27 are mounted for reciprocation in the respective cylinders 23 and are 10 operated by means to be described, their reciprocation being timed with respect to the successive registering of the associated cylinder passages 24 with the pintle ports 25 so as to effect valved intake and discharge of fluid. The timing of the 15 reciprocation of the pistons with respect to the registering of the piston passages 24 with the pintle ports 25 is well understood in the art and need not be explained in detail.

In accordance with the present invention novel 20 and improved means are provided for effecting reciprocation of the pistons relatively to their associated cylinders. In the form shown this is accomplished through the provision of a novel 25 rotatable thrust-transmitting ring assembly, means for transmitting driving torque from the cylinder barrel directly to the thrust ring assembly independently of the pistons and means for transmitting thrust from the ring assembly to the pistons. The thrust ring assembly as shown 30 comprises an outer ring part 28 formed with a cylindrical outer surface mounted for rotation by roller bearings 29 guided in races 30 formed in the inner cylindrical surface of a non-rotatable ring 31. The ring 31 may be set in a fixed position eccentric to the axis of the pintle if the pump is of the constant discharge type or, if it is required that the discharge be variable at will, the ring may be mounted for shifting movement transversely of the pintle axis and may be provided with rods 32 for effecting such shifting movements.

The outer ring part 28 is formed with cylindrical inner surfaces 33-33 separated by an inwardly extending flange 34 located intermediate 45 the end faces of the ring part 28. The surfaces 33 extend continuously around the entire inside of the ring part 28.

Radially outward beyond each cylinder is a 50 pair of thrust blocks 35-35 having arcuate outer surfaces mating with the surfaces 33 of the ring part 28, the blocks of each pair being separated by means of the flange 34. The inner surfaces of the blocks 35 are flat and in the 55 completely assembled thrust ring these flat or bearing surfaces extend perpendicularly with respect to the axis of the associated piston and cylinder assembly. Preferably, the thrust block inner surfaces are formed with wells 35a for receiving roller bearings to be described later. 60 The blocks 35 are maintained in position by means of cheek plates 36 formed with peripheral flanges 37 through which are passed screws 38 having threaded connection with the outer ring part 28 by means of which the cheek plates are secured firmly to the ring part 28. The inner faces of the cheek plates clamp the thrust blocks 35 securely against the opposite sides of the flange 34.

The cheek plates are provided with flanges 39 70 which extend inwardly (towards the common plane of the piston and cylinder assemblies), these flanges being formed with bearing surfaces which are spaced radially inward from the associated thrust blocks 35 and which are parallel 75 to the inner or bearing surfaces provided by the

thrust blocks, and parallel to the bottoms of the bearing wells 35a.

In order to transmit thrust between the thrust ring assembly and the pistons there is provided a plurality of slide blocks generally designated 40, one being connected to each piston and to the thrust ring assembly. As shown in Figures 3 and 4 each slide block is of one piece construction and comprises side portions 41-41 and end portions 42-42, the slide block as a whole thereby constituting a hollow rectangle. The piston associated with each slide block is formed with a flat extension 43 which extends between the side portions 41-41 of the slide block, being connected to the latter by means of a pin 44 passing through the extension 43 and the side portions 41-41. The reduction of the piston to form the flat extension 43 provides a resultant shoulder 45 which is in engagement with the bottom of the slide block. The arrangement therefore is such that during rotation of the thrust ring assembly by means to be described later, movement of the slide block outwardly with respect to the pintle will effect an outward or suction stroke of the connected piston through the medium of the connecting pin 44. As will be understood, only a relatively small effort or force is required to move the piston on its suction stroke so that the wear on the pin will be negligible. On the other hand when, during rotation of the thrust ring assembly, the slide block is moved inwardly with respect to the pintle, force for moving the piston inwardly on its discharge stroke will be transmitted directly from the bottom of the slide block to the shoulders 45 on the piston. Tremendous effort or force is required to move the piston inwardly on its high pressure discharge stroke and by transmitting such force directly from the slide block to the piston I am able to eliminate entirely any wear which otherwise would result in connections of the conventional type heretofore employed between cross heads or slide blocks and pistons.

In most pumps of the prior art it has been customary to transmit torque from the cylinder barrel to the thrust ring by means of the pistons themselves. This necessarily produces a compound bending, shearing, and thrust compression stress in the pistons resulting in flexing and vibration of the pistons which, in turn, results in noisy pump operation and premature wear. Wear of the pistons and/or cylinders of course results in excessive hydraulic slip rendering the pump unsuitable for high pressure loads. In order to avoid these undesirable characteristics I have formed the cylinder barrel with extensions 46, there being two extensions associated with each cylinder and piston. As shown most clearly in Figures 2 and 4, the extensions 46 associated with each cylinder and piston extend up into the opening between the side portions 41-41 of the associated slide block, the extensions being formed to have sliding engagement with the portion of the piston extending between the slide block side portions 41.

Preferably, torque is transmitted from these extensions to the slide blocks through the medium of anti-friction bearings. In the form shown the end portions 42 of the slide blocks are formed with wells 47-47 serving to house roller bearings 48-48 which engage the cylinder barrel extensions 46-46. Preferably, the roller bearing elements 48 are of small diameter and are so dimensioned that there is an overall clearance between the bearings and the ends of the wells 47 amount- 75

ing to about one-fourth of the piston stroke in order to provide for reciprocating movement of the bearings within the wells. With this arrangement the openings between contiguous bearing 5 elements and between the end bearing elements and the ends of the wells will be of such size as to maintain a supply of oil drawn in by capillary attraction and surface tension. By virtue of this arrangement the roller bearings will roll individually while the entire bearing assembly reciprocates bodily. The assembly therefore provides the advantages of roller bearings combined with those of an oil film bearing.

In the form shown in Figures 1 to 4, inclusive, 15 the slide blocks also are formed with bottom wells 49-49 which receive roller bearings 50 engaging the inner bearing surfaces 39 of the cheek plates. Similar roller bearing elements 50 are disposed in the thrust block wells 35^a. The bearings 50 20 preferably are so dimensioned as to leave a total overall clearance between contiguous roller bearings and between the end roller bearings and the ends of the well amounting to about one-fourth of the piston stroke, thereby obtaining the advantages set forth above with reference to the bearing assemblies 48.

In order that the slide blocks 40 may reciprocate with respect to the ring assembly with a minimum of friction the cheek plates are formed 30 with clearance spaces 51, the arrangement being such that the slide blocks are connected to the ring assembly only through the medium of the roller bearings 48 and the capillary oil films therebetween.

35 In order to stiffen the thrust ring assembly so as to still further avoid vibration, bolts 52 are passed through the right hand cheek plate 36 and screwed into the left hand cheek plate. As shown in Figure 2 these bolts are disposed between adjacent slide blocks and are positioned on a circle of a diameter somewhat less than the overall diameter of the thrust ring assembly. The cheek plates are thus joined together on two diameters so as to provide for an extremely rigid 45 assembly.

It will be observed that because of the arcuate formation of the outer surfaces of the thrust blocks 35 the blocks will be permitted to align themselves with respect to the outer faces of 50 the associated slide blocks during assembly and before the cheek plates have been drawn tight against the outer ring part 28. This not only makes for perfect alignment of the parts of the completely assembled thrust ring, but renders 55 it possible to obtain the desired accurate alignment with reduced machining costs. It will be clear that the inner bearing surfaces 33 of the outer ring part 28, being cylindrical, may be machined accurately at a cost which is considerably 60 less than would be the cost of machining flat surfaces in this part for cooperation with the slide blocks. If the bearing surfaces to cooperate with the slide blocks were to be machined in the thrust ring proper, then it would be necessary to set 65 up the machine tool for five accurate machining operations, (in a pump embodying five piston and cylinder assemblies). On the other hand, by virtue of the construction disclosed herein, it is necessary only to set up the machine tool for 70 one accurate machining operation insofar as it is necessary to provide accurately aligned surfaces for cooperating with the outer faces of the slide blocks. In other words, in the construction disclosed herein, the accuracy of alignment of 75 the bearing surfaces cooperating with the outer

faces of the slide blocks is provided for by the self-aligning of the thrust blocks 35 during assembly.

In the modification shown in Figures 5 to 9, inclusive, the construction is similar with the exception that the slide blocks, instead of being formed in one piece, are built up from two side plates and connecting roller elements. The modified form of slide block generally designated 53 comprises two side plate parts 54 which receive the piston connecting pin 44 which extends through the flat extension 43 of the associated piston. The torque transmitting cylinder extensions 46-46 extend between the side plates 54 and in sliding contact with the flat piston extension. 10 The side plates 54 of the slide block 53 are connected by means of rollers 55 journaled in the plates 54, there being two rollers at each end spaced from each other. Each roller 55 is formed with an enlarged part 56 which engages the associated cylinder extension 46. These rollers serve to transmit torque from the cylinder extensions 15 to the slide blocks and the thrust ring assembly. 20

The machines disclosed herein embody the invention in practical and the at present preferred forms, but it will be understood that various changes may be made in the construction and relative arrangement of the parts without departing from the invention as defined in the claims.

I claim:

1. In a hydraulic pump or motor the combination of a plurality of rotatable radial piston and cylinder assemblies each including a relatively non-reciprocable member and a relatively reciprocable member; a rotatable ring assembly provided with parallel outer and inner bearing surfaces perpendicular to the axes of the respective piston and cylinder assemblies; and means for transmitting force between said ring assembly and the reciprocable members of said piston and cylinder assemblies comprising for each piston and cylinder assembly a slide block, roller bearing elements disposed between said slide block and said bearing surfaces, means for transmitting driving torque directly between the non-reciprocable member and said slide block, a pintle connection between the slide block and the relatively reciprocable member for transmitting force therebetween during movement of the relatively reciprocable member in one direction, and a separate and independent connection for transmitting force between said slide block and said relatively reciprocable member during movement of the latter in the opposite direction, said last named connection comprising a shoulder on said relatively reciprocable member with which the slide block is in direct driving engagement.

2. In a hydraulic pump or motor the combination of a plurality of rotatable radial piston and cylinder assemblies each including a relatively non-reciprocable member and a relatively reciprocable member; a rotatable ring assembly provided with parallel outer and inner bearing surfaces perpendicular to the axes of the respective piston and cylinder assemblies; and means for transmitting force between said ring assembly and the reciprocable members of said piston and cylinder assemblies comprising for each piston and cylinder assembly a slide block mounted for sliding movements between and in engagement with the associated inner and outer bearing surfaces, roller bearing elements for transmitting driving torque directly between the non-reciprocable member and said slide block, a pintle

connection between the slide block and the relatively reciprocable member for transmitting force therebetween during movement of the relatively reciprocable member in one direction, and 5 a separate and independent connection for transmitting force between said slide block and said relatively reciprocable member during movement of the latter in the opposite direction, said last named connection comprising a shoulder on said 10 relatively reciprocable member with which the slide block is in direct driving engagement.

3. In a hydraulic pump or motor the combination of a plurality of rotatable radial piston and cylinder assemblies each including a relatively 15 non-reciprocable member and a relatively reciprocable member; a rotatable ring assembly comprising an outer ring part provided with an inwardly extending flange intermediate its end faces, spaced thrust blocks having arcuate outer 20 surfaces engaging the inner curved surface of said outer ring part and abutting on opposite sides of said flange, cheek plates secured to the opposite sides of said outer ring part and clamping said thrust blocks against said flange, there 25 being a thrust block for each piston and cylinder assembly and each thrust block having an inner bearing surface substantially perpendicular to the axis of the associated piston and cylinder assembly, said cheek plates being provided with 30 bearing surfaces radially spaced inwardly from the respective thrust blocks; slide blocks, one mounted between each of the respectively associated thrust blocks and cheek plate bearing surfaces; and connections between the reciprocable 35 elements of said piston and cylinder assemblies and the respectively associated slide blocks.

4. In a hydraulic pump or motor the combination of a plurality of rotatable radial piston and cylinder assemblies each including a relatively 40 non-reciprocable member and a relatively reciprocable member; a rotatable ring assembly comprising an outer ring part provided with an inwardly extending flange intermediate its end faces, spaced thrust blocks having arcuate outer 45 surfaces engaging the inner curved surface of said outer ring part and abutting on opposite sides of said flange, cheek plates secured to the opposite sides of said outer ring part and clamping said thrust blocks against said flange, there 50 being a thrust block for each piston and cylinder assembly and each thrust block having an inner bearing surface substantially perpendicular to the axis of the associated piston and cylinder assembly, said cheek plates being provided 55 with bearing surfaces radially spaced inwardly from the respective thrust blocks; slide blocks, one mounted between each of the respectively associated thrust blocks and cheek plate bearing surfaces; roller bearings disposed between the 60 inner and outer faces of the slide blocks and the thrust blocks and cheek plate bearing surfaces respectively; and connections between the reciprocable elements of said piston and cylinder assemblies and the respectively associated slide blocks.

5. In a hydraulic pump or motor the combination of a plurality of rotatable radial piston and cylinder assemblies each including a relatively 65 non-reciprocable member and a relatively reciprocable member; a rotatable ring assembly comprising an outer ring part provided with an inwardly extending flange intermediate its end faces, spaced thrust blocks having arcuate outer 70 surfaces engaging the inner curved surface of said outer ring part and abutting on opposite

sides of said flange, cheek plates secured to the opposite sides of said outer ring part and clamping said thrust blocks against said flange, there 5 being a thrust block for each piston and cylinder assembly and each thrust block having an inner bearing surface substantially perpendicular to the axis of the associated piston and cylinder assembly, said cheek plates being provided with bearing surfaces radially spaced inwardly from the respective thrust blocks; slide blocks, one 10 mounted between each of the respectively associated thrust blocks and cheek plate bearing surfaces; connections between the reciprocable elements of said piston and cylinder assemblies and the respectively associated slide blocks; and means for transmitting torque directly between the non-reciprocable members of the piston and cylinder assemblies and said ring assembly independently of said reciprocable members.

6. In a hydraulic pump or motor the combination of a plurality of rotatable cylinder and piston assemblies each including a relatively non-reciprocable member and a relatively reciprocable member; a rotatable ring assembly comprising a ring part surrounding said piston and cylinder assemblies, a flange extending around the inner surface of said ring part, a plurality of thrust blocks positioned to abut the inner surface of said ring part, there being a pair of thrust blocks for each piston and cylinder assembly and the blocks of each pair being positioned respectively on opposite sides of said flange and abutting the side faces thereof, and cheek plates removably secured to the opposite sides of said ring part and engaging said thrust blocks and clamping the latter against said flange, said cheek plates being provided with inner bearing surfaces respectively spaced from and facing said thrust blocks; slide blocks interposed between and being slidably supported by the thrust blocks and the associated inner bearing surfaces; and means connecting the slide blocks respectively with the relatively reciprocable elements of the piston and cylinder assemblies.

7. In a hydraulic pump or motor the combination of a plurality of rotatable cylinder and piston assemblies each including a relatively non-reciprocable member and a relatively reciprocable member; a rotatable ring assembly comprising a ring part surrounding said piston and cylinder assemblies, a flange extending around the inner surface of said ring part, a plurality of thrust blocks positioned to abut the inner surface of said ring part, there being a pair of thrust blocks for each piston and cylinder assembly and the blocks of each pair being positioned respectively on opposite sides of said flange and abutting the side faces thereof, and cheek plates removably secured to the opposite sides of said ring part and engaging said thrust blocks and clamping the latter against said flange, said cheek plates being provided with inner bearing surfaces respectively spaced from and facing said thrust blocks; slide blocks interposed between and being slidably supported by the thrust blocks and the associated inner bearing surfaces; means for transmitting force in one direction between each of the relatively reciprocable members and the respectively associated slide blocks; and other means for transmitting force in the opposite direction between each of the relatively reciprocable members and the respectively associated slide blocks.

8. In a hydraulic pump or motor the combination of a plurality of rotatable cylinder and piston assemblies each including a relatively non-recip-

rocable member and a relatively reciprocable member; a rotatable ring assembly comprising a ring part surrounding said piston and cylinder assemblies, a flange extending around the inner 5 surface of said ring part, a plurality of thrust blocks positioned to abut the inner surface of said ring part, there being a pair of thrust blocks for each piston and cylinder assembly and the blocks of each pair being positioned respectively 10 on opposite sides of said flange and abutting the side faces thereof, and cheek plates removably secured to the opposite sides of said ring part and engaging said thrust blocks and clamping the latter against said flange, said cheek plates being 15 provided with inner bearing surfaces respectively spaced from and facing said thrust blocks; slide blocks interposed between and being slidably supported by the thrust blocks and the associated inner bearing surfaces; means connecting the slide 20 blocks respectively with the relatively reciprocable elements of the piston and cylinder assemblies; and means for transmitting driving torque between the relatively non-reciprocable elements and the ring assembly independently of the relatively reciprocable elements.

9. In a hydraulic pump or motor the combination of a plurality of rotatable cylinder and piston assemblies each including a relatively non-reciprocable member and a relatively reciprocable member; a rotatable ring assembly comprising a ring part surrounding said piston and cylinder assemblies, a flange extending around the inner surface of said ring part, a plurality of thrust blocks positioned to abut the inner surface of 35 said ring part, there being a pair of thrust blocks for each piston and cylinder assembly and the blocks of each pair being positioned respectively on opposite sides of said flange and abutting the side faces thereof, and cheek plates removably 40 secured to the opposite sides of said ring part and engaging said thrust blocks and clamping the latter against said flange, said cheek plates being provided with inner bearing surfaces respectively spaced from and facing said thrust blocks; 45 slide blocks interposed between and being slidably supported by the thrust blocks and the associated inner bearing surfaces; means connecting the slide blocks respectively with the relatively reciprocable elements of the piston and cylinder 50 assemblies; and means including roller bearing elements for transmitting driving torque between the relatively non-reciprocable elements and the ring assembly independently of the relatively reciprocable elements.

55 10. In a hydraulic pump or motor the combination of a plurality of rotatable radial piston and cylinder assemblies each including a relatively non-reciprocable member and a relatively reciprocable member; a rotatable ring assembly provided with parallel outer and inner bearing surfaces perpendicular to the axes of the respective piston and cylinder assemblies; and means for transmitting force between said ring assembly and the reciprocable members of said piston and cylinder assemblies comprising for each piston and cylinder assembly a slide block, roller bearing elements disposed between said slide block and said bearing surfaces, means for transmitting driving torque directly between the non-reciprocable member and said slide block, said ring assembly and slide block being so formed and relatively arranged that force is transmitted between the slide block and ring assembly only through said roller bearings, a pintle connection 70 between the slide block and the relatively recip-

rocable member for transmitting force therebetween during movement of the relatively reciprocable member in one direction, and a separate and independent connection for transmitting force between said slide block and said relatively reciprocable member during movement of the latter in the opposite direction, said last named connection comprising a shoulder on said relatively reciprocable member with which the slide block is in direct driving engagement.

11. In a hydraulic pump or motor the combination of a plurality of rotatable radial piston and cylinder assemblies each including a relatively non-reciprocable member and a relatively reciprocable member; a rotatable ring assembly comprising an outer ring part surrounding said piston and cylinder assemblies and having a cylindrical outer surface and a cylindrical inner surface provided with an inwardly extending flange intermediate the end faces of said ring part, spaced 20 thrust blocks having arcuate outer surfaces engaging the inner curved surfaces of said outer ring part and abutting on opposite sides of said flange, cheek plates secured to the opposite sides of said outer ring part and clamping said thrust blocks against said flange, there being a thrust block for each piston and cylinder assembly and each thrust block having an inner bearing surface substantially perpendicular to the axis of the associated piston and cylinder assembly, said cheek plates being provided with bearing surfaces radially spaced inwardly from the respective thrust blocks, said cheek plates extending within and engaging the cylindrical inner face of said outer ring part and having peripheral flanges 30 abutting against the end faces thereof, screws passing through said peripheral flanges for securing said cheek plates to said outer ring part, and bolts connecting said cheek plates to each other and being circumferentially spaced on a 40 circle within and concentric with the outer ring part; slide blocks, mounted one between each of the respectively associated thrust blocks and cheek plate bearing surfaces; connections between the reciprocable elements of said piston 45 and cylinder assemblies and the respectively associated slide blocks; and means surrounding the outer ring part of the rotatable ring assembly and supporting the latter for rotary movements.

12. In a hydraulic pump or motor the combination of a plurality of rotatable radial piston and cylinder assemblies each including a relatively non-reciprocable member and a relatively reciprocable member; a rotatable ring assembly provided with parallel outer and inner bearing surfaces perpendicular to the axes of the respective piston and cylinder assemblies; and means for transmitting force between said ring assembly and the reciprocable members of said piston and cylinder assemblies comprising for each piston and cylinder assembly a slide block mounted for relative translatory movements between the associated inner and outer bearing surfaces, the face of said block adjacent to one of said bearing surfaces being formed with a well, a plurality of 60 roller elements in said well for transmitting force between said bearing surface and said slide block, there being a total aggregate clearance between said roller elements and the ends of said well amounting to about one-fourth the normal stroke 65 of the relatively reciprocable member of the associated piston and cylinder assembly, means for transmitting driving torque directly between the non-reciprocable member and said slide block, a connection between the slide block and the rela- 70 75

tively reciprocable member for transmitting force therebetween during movement of the relatively reciprocable member in one direction, and a separate and independent connection for transmitting force between said slide block and said relatively reciprocable member during movement of the latter in the opposite direction.

13. In a hydraulic pump or motor the combination of a plurality of rotatable radial piston and cylinder assemblies each including a relatively non-reciprocable member and a relatively reciprocable member; a rotatable ring assembly provided with parallel outer and inner bearing surfaces perpendicular to the axes of the respective piston and cylinder assemblies; and means for transmitting force between said ring assembly and the reciprocable members of said piston and cylinder assemblies comprising for each piston and cylinder assembly a slide block mounted for sliding movements between and in engagement with the associated inner and outer bearing surfaces, means for transmitting driving torque directly between the non-reciprocable member and said slide block, the face of said block adjacent to said torque-transmitting means being formed with a well, a plurality of roller elements in said well for transmitting torque, there being a total aggregate clearance between said elements and the ends of said well amounting to about one-fourth the normal stroke of the relatively reciprocable member of the associated piston and cylinder assembly, a connection between the slide block and the relatively reciprocable member for transmitting force therebetween during movement of the relatively reciprocable member in one direction, and a separate and independent connection for transmitting force between said slide block and said relatively reciprocable member during movement of the latter in the opposite direction.

14. In a hydraulic pump or motor the combination of a plurality of rotatable radial piston and cylinder assemblies each including a relatively non-reciprocable member and a relatively reciprocable member; a rotatable ring assembly provided with parallel outer and inner bearing surfaces perpendicular to the axes of the respective piston and cylinder assemblies; and means for transmitting force between said ring assembly and the reciprocable members of said piston and cylinder assemblies comprising for each piston and cylinder assembly a slide block assembly comprising spaced plate parts mounted for sliding movements between the associated inner and outer bearing surfaces, means connecting said

spaced plate parts to the relatively reciprocable member of the associated piston and cylinder assembly, a torque-transmitting part fast with the relatively non-reciprocable member of the associated piston and cylinder assembly, and a roller bearing member joining the spaced plate parts of said slide block assembly and having rolling contact with said torque-transmitting part.

15. In a hydraulic pump or motor the combination of a plurality of rotatable radial piston and cylinder assemblies each including a relatively non-reciprocable member and a relatively reciprocable member; a rotatable ring assembly comprising an outer part surrounding said piston and cylinder assemblies in spaced relation thereto; a plurality of slide blocks having inner and outer bearing surfaces; connections between said slide blocks and the respective reciprocable members; a plurality of segmental thrust blocks abutting the inner face of said outer ring part and having bearing connection with the outer surfaces of said slide blocks, there being a pair of such thrust blocks associated with each slide block; means other than the slide blocks for spacing the thrust blocks of the respective pairs from each other; means for clamping the thrust blocks against said spacing means; and means providing inner bearing surfaces facing the respective thrust blocks and having bearing connection with the inner surfaces of said slide blocks.

16. In a hydraulic pump or motor the combination of a plurality of rotatable radial piston and cylinder assemblies each including a relatively non-reciprocable member and a relatively reciprocable member; a rotatable ring assembly comprising an outer part surrounding said piston and cylinder assemblies in spaced relation thereto; a plurality of slide blocks; connections between said slide blocks and the respective reciprocable members; a plurality of segmental thrust blocks abutting the inner face of said outer ring part and having bearing connection with the outer surfaces of said slide blocks, there being a pair of such thrust blocks associated with each slide block; means other than the slide blocks for spacing the thrust blocks of the respective pairs from each other; means for clamping the thrust blocks against said spacing means; and means for transmitting torque directly between said slide blocks and said non-reciprocable members independently of said reciprocable members.
